CONCRETE FORM SUPPORTING DEVICE

Filed April 22, 1932

By

Frank J. Clements

Attorney

UNITED STATES PATENT OFFICE

WILLIAM G. COPESTAKE, OF NEWARK, NEW JERSEY, ASSIGNOR TO CONCRETE CONSTRUCTION ACCESSORIES CO., OF IRVINGTON, NEW JERSEY

CONCRETE FORM SUPPORTING DEVICE

Application filed April 22, 1932. Serial No. 606,972.

My invention relates to improvements in supports or hangers for concrete building forms and more particularly to means for adjustably and releasably supporting and spacing parallel series of adjacent pan-shaped metal forms such as are used in the construction of concrete floors having exposed integral joists.

In the construction of concrete floors of buildings it is the practice to support transverse series of wooden joists upon shores which are erected between the floor levels for the purpose of removably supporting metal floor forms, the forms being usually pan-shaped.

To uniformly support the form pans in horizontal spaced rows extending from one floor girder to another, long furring strips are usually nailed to the opposite side faces of the joists and separator strips or spreaders are rested at intervals upon the furring strips to uniformly space the joists and provide supports for the side edges of the pans. Such a construction of all wooden false work has proven adequate for properly supporting the form pans, but the costs incident to assembling and disassembling of the wooden supports to drop the pans, due to the waste of time and materials during such operations, make the use of such a construction prohibitive on many jobs.

Many attempts have therefore been made to simplify the pan supporting structure by substituting for the nailed furring strips and spacers, various forms of metal hangers which may be adjusted along the joists and on which the pans may be adjustably supported. While such metal hangers have overcome certain disadvantages of the all wooden construction by providing means which may be repeatedly used and adjusted to a degree to meet the requirements of such use, they have however been characterized by an elaborate arrangement of parts expensive to manufacture and time consuming and wasteful to

assemble and disassemble for repeated use on a job. Such prior art devices have further required the removal of several parts or the total destruction of such parts in order to drop the form pans and reassemble the parts for repeated use.

It is, therefore, the primary object of my invention to eliminate such faults and disadvantages as pointed out above and to provide a simple, compact and reliable hanger which may be economically manufactured and repeatedly used without the loss of time and materials common to the use of such prior art devices.

A further object of my invention is to provide a strong and durable pan form support or hanger on which pans may be assembled and adjusted from above or below the false work and which is so constructed as to permit ready removal of the supporting elements to drop the pans after the concrete is set without mutilation of any portion of the pan form or its support.

A still further object of my invention is to provide a hanger member which may be readily mounted upon and adjusted along a supporting joist, said member having spaced means for laterally receiving and vertically and transversely bracing one or more pan form supporting elements.

Another object of my invention relates to adjustable pan form supporting means of the character described with which may be combined a spreader, the supporting means and spreader being operable as a unit in the operations of assembling pan forms upon or releasing them from the false work.

Another object of my invention is to provide a hanger and spreader of the character described which may be economically manufactured and which will require the minimum of time and labor in its application to and removal from the form supporting joists of the false work.

Referring now to the accompanying draw-

ing, which is made a part hereof, and on which similar reference characters indicate similar parts:

5 Fig. 1 is a vertical sectional view of a concrete floor, shown in the process of construction, with the false work and form pans in perspective to illustrate the operative relationship of my improved form pan hangers to the pans and joists of the false work;

10 Fig. 2 is an enlarged sectional view of one of the false work joists showing the adjustable mounting of the form pan supporting clips and means for attaching a spreader bar thereto;

15 Fig. 3 is a fragmentary side elevation of the joist and pan hanger shown in Fig. 2 with the pan removed from the adjustable supporting clip; and

20 Fig. 4 is a perspective view of one of the adjustable, pan supporting clips removed from the hanger strap and showing in dotted lines the manner of supporting the ends of adjacent pans thereon.

25 In the drawing, the parts indicated as A represent the usual wooden joists which are supported by shores, not shown. These joists constitute portions of the false work, referred to in the introduction of this specification as erected between the floor levels of a 30 building to temporarily support the removable form pans B, on which pans concrete C, is poured to form the floor and depending, integral concrete joists. All of these parts, not 35 specifically referred to herein, may be of any well-known or approved construction and design, provided they do not depart from the spirit of my invention.

40 Straddling each of the adjacent joists A (see Fig. 1) are strap-like hanger members 2. These hanger members are preferably arranged at spaced intervals along each joist with the hangers of one joist disposed diametrically opposite the hangers of adjacent joists and secured in place thereon by a suitable anchoring means such as the nail 3, shown in Fig. 2.

45 The hanger straps 2 are preferably made from a strip of sheet metal bent into inverted U-shape formation providing a relatively short flattened central portion 4 adapted to rest upon the upper edge of a joist, and spaced depending leg portions 5 adapted to embrace opposite sides of the joist. The legs 5 of the hanger are each formed with a series of spaced, vertically disposed, rectangular embossed portions 6 which are slotted at opposite sides to provide laterally opening pockets 7.

50 60 To provide simple hanger carrying means for adjustably supporting the form pans B at the desired levels and adjacent the sides of the joists A, which means may be readily removed without mutilation to drop the pans, I have provided each leg 5 of the hanger

straps 2 with a laterally removable supporting clip 8.

65 The pan supporting clips 8, each comprise a rectangular deck formed at one end with an upturned pan retaining flange 9, and at 70 one side with a downwardly bent flange portion 10, the latter portion having a rearwardly bent laterally extending bracket arm portion 11. By reference to Figs. 2 and 3 it will be noted that the bracket arm portion 75 11 of the clip is of such dimensions as to be readily inserted into a selected pocket 7 in the leg 5 of a hanger 2, where the clip 8 will be vertically supported and transversely braced by the adjacent cooperating walls of 80 the rectangular embossed portions 6 and hanger strap 2.

85 As it is desirable in certain construction of false work to employ spacer bars or spreaders 12, such as are shown at intervals 90 between the wooden joists A, I have formed the downwardly turned flange 10 of each clip member 8 with an aperture 13. Apertures are also formed adjacent the ends of the spreader bars 12 to register with the apertures in clip flanges 10 and suitable securing means such as bolts 14 are inserted through the apertures to secure the members together.

95 By this construction a clip member 8 may be secured to each end of a spreader bar 12 and the assembly applied as a unit between adjacent joists A by inserting the laterally turned arms 11 at each end of the bar into selected pockets 7 of the hangers 2 positioned upon the joists. Likewise, each pair of form 100 pan supporting clips 8 and attached spreader bar 12 may be removed from the laterally opening pockets 7 in the hangers, as a unit, to drop the pans after the concrete is set, by a reverse lateral movement of the assembly 105 relative to the hanger.

110 Obviously, when desired, the clip members 8 may be used individually with the hanger members to support the form pan from the false work and when so used require no additional means to secure the parts in desired adjusted positions.

115 It is also important to note that the pan supporting clips are always movable in planes parallel to the lower edges of the pans when inserting them into the supporting pockets of hanger members and when removing them therefrom, thus greatly reducing the time and apparatus required for these operations and permitting the parts to be 120 repeatedly used.

125 While I have shown and described but one embodiment of my invention, it is to be understood that it is capable of many modifications. Changes, therefore, in the construction and arrangement may be made which do not depart from the spirit and scope of my invention, as covered by the appended claims.

I claim:

1. A concrete form support for open bottom pans comprising a hanger member having a vertical series of spaced, laterally opening pocket forming portions, and a form supporting clip element having an offset arm laterally insertable within said portions and supported thereby.

2. A concrete form support for open bottom pans comprising a hanger member having a laterally opening pocket forming portion, and a form supporting clip having a bracket arm laterally insertable within said portion and supported thereby, said clip having flange means engaging the edge of a pan to prevent transverse collapse thereof.

3. A concrete form support for open bottom pans comprising a hanger strap having a series of spaced, vertically disposed, rectangular embossed portions, said embossed portions being slotted at the sides to provide laterally opening pockets, and a form supporting and retaining clip element having a bracket arm laterally insertable within said slotted embossed portions and supported thereby.

4. Means for supporting form pans on false work joists, comprising pocketed hanger members carried by the joists, and clip elements laterally insertable within the pockets of said hangers, each clip element having means for holding a pan in position thereon.

5. Means for supporting form pans on false work joists, comprising pocketed hanger members carried by said joists, form-supporting clip elements each having an offset arm laterally insertable within the pockets of said hangers, and a spreader bar connected to adjacent clip elements between the joists, whereby a pair of clip elements may be removed from their supporting pockets as a unit to drop the form pans.

6. Means for supporting form pans on false work joists, comprising pocketed hanger members carried by the joists, spreader bars extending between the joists, and clip elements, each element having integral means for supporting engagement with a form pan, for connection to a spreader bar and for insertion into a pocket of a hanger member.

7. In supporting means for concrete forms adapted to be set up on temporary joists, a form supporting clip element having flange means for engaging and supporting a form and a bracket arm extending at right angles to said flange means and adapted to be secured parallel with said joists.

In testimony whereof I affix my signature.
WILLIAM G. COPESTAKE.
